UNITED STATES PATENT OFFICE.

ANSON C. MILLS, OF JACKSON, MICHIGAN.

WIRE-WORKING MACHINE.

SPECIFICATION forming part of Letters Patent No. 720,170, dated February 10, 1903.

Application filed September 22, 1902. Serial No. 124,303. (No model.)

To all whom it may concern:

Be it known that I, ANSON C. MILLS, a citizen of the United States, residing at Jackson, in the county of Jackson and State of Michigan, have invented certain new and useful Improvements in Wire-Working Machines; and I do hereby declare the following to be a full, clear, and exact description of the invention, such as will enable others skilled in the art to which it appertains to make and use the same.

My invention relates to improvements in wire-working machines, and more particularly to improved means for winding the ends 15 of the transverse wires of a fence around the longitudinal wires of the same, and adapted to be used in a machine of the character shown and described in Patent No. 698,533, to myself and George R. Lamb, dated April 29, 1902; and its object is to provide an automatic device operating in conjunction with such wire-fence machine to wind the ends of the transverse wires around the upper and lower longitudinal wires of the fence and to 25 provide the same with certain new and useful features, hereinafter more fully described, and particularly pointed out in the claims, reference being had to the accompanying drawings, in which—

Figure 1 is a side elevation of a device embodying my invention shown with the parts in position to commence winding the transverse wire. Fig. 2 is a front elevation of the same, taken at right angles to Fig. 1. Fig. 3 is a plan view of the same, and Fig. 4 an enlarged detail of the end of the winding member.

Like letters refer to like parts in all of the figures.

A represents a portion of the frame of the 40 machine; B, a shaft of the machine on which a part of the machinery for making the fence is mounted, as shown in the patent referred to.

C is a grooved wheel rotating with the shaft B and having mounted thereon the winding 45 mechanism by means of a suitable bracket E, securely attached to the wheel C and rotating therewith. In a bearing D on this bracket and located partially within a recess in the rim of the wheel C is mounted a short rotating shaft F, having on one end a suitable beveled gear K, engaging a larger beveled gear L, said gears being so proportioned as

to rotate the shaft F as many times to one revolution of the gear L as is desired to wind the transverse wire around the longitudinal 55 wire. This gear L is fixed on a shaft N, journaled in the bracket E, on which shaft is an intermittent pinion M, having a portion of its periphery adapted to engage the smooth surface R of an intermittent gear P, having a 60 series of cogs Q in a sufficient number to rotate the pinion M one revolution. This gear P is held from rotating by bolts O, engaging the frame A. The shaft F is arranged with its axis in the plane of the groove in the 65 wheel C and the bearing D, shaft F, and the beveled pinion K are slotted longitudinally, as at S, to permit the wire to enter to the axis of the same. This wire I represents either the upper or the lower longitudinal wire of 70 the fence.

J represents one of the transverse wires of the fence, and J' indicates the manner in which it is wound around the wire I, as hereinafter described. To effect this winding, 75 the shaft F is provided on its end opposite to the pinion K with a lug G at one side of its axis to engage the wire J and wind it around the wire I and a cam H at the other side of the same to engage the wire J and move it longitudinally of the wire I.

The operation of my device is as follows: The wheel C revolves with the shaft B and carries the winding mechanism around the axis of the shaft, and during that part of the 85 revolution where the wheel M is opposite the plane surface R of the gear P the shaft N does not rotate in the bracket. When the device reaches the position shown in Fig. 1, the wire I is in the slot S and in the axis of the shaft 90 F, bearing D, and pinion K, and the wire J is engaged by the lug G. At this point the teeth of the intermittent pinion M engage the teeth Q on the stationary intermittent gear P, and the shaft N is rotated one revolution upon its 95 axis, which in turn rotates shaft F, and thus winds the wire J around the wire I. The cam-surface H pushes the coil backward away from the end of the shaft F to insure the spiral winding and the passage of the end of the lug 100 G clear of the main portion of the wire J as it revolves around the wire I. The shaft F having made the required number of revolutions in this way stops with the slot S in the

proper alinement to release the wire I, and the operation is again repeated at each revolution of the wheel C. If desired to space the wires J a less distance apart than the circumference of the wheel C, additional winding devices, such as shown, may be attached to the wheel at proper intervals, and thus an increased number of wires to each revolution of the wheel may be wound around the wire I as occasion requires.

Having thus fully described my invention, what I claim, and desire to secure by Letters Patent, is—

1. In combination with means for winding a wire around another wire substantially as described, a cam-surface on said means adapted to engage the wound wire and move it longitudinally of the other wire.

2. The combination of a shaft having a longitudinal slot extending to its axis to receive a longitudinal wire, a lug on the shaft to engage a transverse wire and wind the same around the longitudinal wire, a cam on the shaft to engage the transverse wire and move it longitudinally of the longitudinal wire, and means for rotating the shaft.

3. The combination of a rotative wheel having a groove in its periphery, a shaft mounted on the periphery of the wheel and having a longitudinal slot in the plane of the groove, 30 a lug and a cam on the end of the shaft and means for imparting intermittent, rotary motion to the shaft at each revolution of the wheel.

4. The combination of a rotative wheel having a groove and a recess in its periphery, a bracket fixed on the wheel, a shaft opposite the recess and journaled in the bracket, a beveled pinion and a lug on the shaft, said bracket, shaft and pinion also having a longitudinal 40 groove in the plane of the groove of the wheel, a bevel-gear engaging the pinion, a fixed intermittent gear near the wheel, and an intermittent pinion engaging the fixed gear and connected to the beveled gear to intermittently rotate the shaft.

In testimony whereof I affix my signature in presence of two witnesses.

ANSON C. MILLS.
